VALVE MECHANISM FOR BURNERS

Filed March 7, 1927

UNITED STATES PATENT OFFICE

HARRISON K. STRICKLER, OF ERIE, PENNSYLVANIA, ASSIGNOR TO THE PROTANE CORPORATION, OF ERIE, PENNSYLVANIA, A CORPORATION OF DELAWARE

VALVE MECHANISM FOR BURNERS

Application filed March 7, 1927. Serial No. 173,351.

Burners operating upon fuel delivered to the burner as a vapor but conveyed to the burner in the form of a liquid have some very serious problems as to control. If the closure mechanisms are remote from the burner a comparatively large volume of volatile liquid is left between the burner and the valve upon the closure of the valve which gradually is vaporized and escapes to the room. Where it has been attempted to place the valve adjacent to the burner with the expansion of the parts incident to the heat of the burner difficulty has been experienced in maintaining the valve in working condition. By the present invention these difficulties are obviated and the valve so placed that very little, if any, liquid remains beyond the closure of the valve upon the closure of the valve. The invention further contemplates the mounting of the valve and the metering devices in a detachable portion so that in servicing a ready change may be made of this critical part without a removal of the main connections leading to the burner. A further feature of the invention contemplates the delivery of the fuel to the hotter parts of the apparatus in such a manner as to prevent the formation of carbon at the vaporizing point. Other features and details of the invention will appear more fully from the specification and claims.

The invention is illustrated in the accompanying drawings as follows:—

Fig. 1 shows a section through the valve control means.

Fig. 2 a perspective view of a portion of a stove with the burner in place therein.

Fig. 3 a plan view of a burner and the control mechanism.

Fig. 4 a section on the line 4—4 in Fig. 1. 1 marks the stove frame, 2 the burner, and 3 the vapor expansion chamber. These are of ordinary construction. Liquid fuel is supplied through a supply pipe 4. This pipe leads into a fitting 5. A supply tube 6 extends from the fitting 5 forwardly to approximately the location of the burner. This may be longer or shorter depending on the location of the burner. A sleeve-shaped valve body 7 is detachably secured by screw threads

8 at the inner end of the tube 6. The sleeve of this body is internally screw-threaded at 9 and a valve plug 10 is screwed into this sleeve. The valve plug carries an extension 11 with a valve head 12 at the end of the extension. The valve 12 operates upon a seat 13 in the body 7 and forms a closure means for the mechanism. A meter pin extension 14 projects from the valve head and carries a metering pin 15. The metering pin extends through a metered opening 16 in the meter cap 17.

An operating stem 18 has a squared end 18a operating in a squared socket 19 in the plug 10, thus forming a slip connection between the operating stem 18 and the plug 10. This sliding connection as clearly shown in the drawings has a very loose fit forming a universal joint permitting the valve to remain concentric with the valve body without binding of the parts, or injuring the seating surfaces. The stem extends through a stuffing box 20 on the fitting 5 and is provided with an operating handle 21.

The plug 10 has fuel passages 22. These are directed outwardly so that the fuel issuing from them strikes the hot walls of the body 7, this body being sufficiently close to the burner to receive heat from the burner.

In operation the stem 18 is turned and this operating on the plug and through the action of the screw opens and closes the valve and operates the metering pin to the position desired. The small jet passages 22 where the liquid is released to a large extent are removed from the heated surfaces and thus prevent the formation of carbon which is apt to occur at this point.

The ready removal of the operating parts involved in the closure valve and the metering pin permit of an exchange of these critical parts in the servicing of the device. The slip joint permits of the expansion and contraction of the tube under heat without undue pressure on the valve.

In the usual construction the application of heat to the drying tube tends to warp this tube out of shape. Warping is also frequently produced in the assembly of the device. This warpage causes binding, or misalign-

ment of the valve parts which either destroys the effectiveness of the valve, or makes it difficult to turn the operating handle. In the present device the universal joint action of the slip connection obviates this condition and permits easy and effective operation of the valve plug 11 even in the most aggravated cases of misalignment. The slip joint permits the operating stem 18 to be locked 10 against axial movement. This facilitates the packing of this stem which is an important feature as the gases, or liquids, used in connection with this burner are very penetrating.

What I claim as new is:—

15 1. In a valve mechanism for burners, the combination of a burner; a supply tube; an internally screw-threaded valve body in heat-receiving relation to the burner and in advance of the supply tube; a valve actuating screw in the body; a valve actuated by the screw; and an operating stem having a universal connection with the screw, said connection being adjacent to the screw.

20 2. In a valve mechanism for burners, the combination of a burner; a supply tube; an internally screw-threaded valve body in advance of the supply tube and in heat-receiving relation to the burner; a screw plug in the body, there being means permitting the 25 passage of fuel past the screw plug; a valve carried by the plug; and an operating stem extending from the plug and having a universal connection with the plug, said connection being adjacent to the plug.

25 3. In a valve mechanism for burners, the combination of a burner; a supply tube; an internally screw-threaded body in advance of the supply tube and in heat-receiving relation to the burner; a screw plug in the body 30 having a fuel passage therethrough, said passage discharging outwardly against the walls of the body; a valve carried by the plug; and an operating stem extending from the plug.

4. In a valve mechanism for burners, the combination of a burner; a supply tube; an internally screw-threaded body in advance of the supply tube and in heat-receiving relation to the burner; a screw plug in the body having a fuel passage therethrough, said passage discharging outwardly against the walls 45 of the body; a valve carried by the plug; and an operating stem extending from the plug and having a slip connection with the plug, the slip connection permitting the passage of fuel therethrough to the fuel passage from the plug.

5. In a valve mechanism for burners, the combination of a burner; a supply tube; an internally screw-threaded valve body in heat-receiving relation to the burner and in advance of the supply tube; a valve actuating screw in the body; a valve actuated by the screw, said connection being adjacent to said screw; an operating stem having a universal 60 connection with the screw; and a metering

pin carried by and extending in advance of the valve.

6. In a valve mechanism for burners, the combination of a burner; a supply tube; a valve body in advance of the supply tube and detachably connected with the tube; a closure valve; a metering pin in the body; and an operating stem extending through the tube and detachably connected with the valve, the connection being adjacent to the valve.

7. In a valve mechanism for burners, the combination of a burner; a supply tube; a valve body in advance of the supply tube and detachably connected with the tube and subjected to the heat of the burner; a closure valve; a metering pin in the body; and an operating stem extending through the tube and detachably connected with the valve, the connection being adjacent to the valve.

8. In a valve mechanism for burners, the combination of a supply tube and internally screw-threaded valve body detachably secured to the tube; a valve plug in the tube body, there being means permitting the passage of fuel past the screw plug; a valve carried by the plug; a metering pin carried by the valve; a valve stem having an universal connection with the valve plug, said connection being adjacent to the plug; and a valve fitting to which the tube is connected and through which the stem extends.

In testimony whereof I have hereunto set my hand.

HARRISON K. STRICKLER.
